UNITED STATES PATENT OFFICE.

NAPOLEON DU BRUL, OF CINCINNATI, OHIO.

DESIGN FOR A CIGAR-CUTTER.

SPECIFICATION forming part of Design No. 12,921, dated May 9, 1882.

Application filed May 26, 1881. Term of patent 14 years.

To all whom it may concern:

Be it known that I, NAPOLEON DU BRUL, of Cincinnati, Hamilton county, Ohio, have invented or produced a new and original Design 5 for a Cigar-Butt Cutter, of which the following is a specification, reference being had to the accompanying drawings, forming part thereof.

Figure 1 is a front elevation of my newly-10 designed cutter. Fig. 2 is a top view of the front portion of the same. Fig. 3 is a rear view of the knife-holder.

The rear journal-bearing, A, is of the represented U form as viewed from above, (see Fig. 15 2,) and appears as resting flat upon the base B, as seen in dotted lines in Fig. 1. The knife-holder C has in its front and rear aspects the irregular crescent-like contour shown in obverse in Fig. 2 and in reverse in Fig. 1. The 20 rear face of the holder is relieved by a projecting marginal bead, c, which also serves to screen or hide from view the edge of the cutter-blade. The holder at its upper extremity, as viewed from above, is seen to expand into 25 a knob-like claviform contour, c'. The throat-

plate D, as viewed from the front, consists of an oblong portion, d, with ogee curves constituting a swell, d' d'', with a central scallop or rounded notch, d''', and on its under edge a scallop, d^{iv}, in the form of an arc. On the left 30 side of the holder appears the portion of a circular disk, E, whose remaining portion is hidden by the holder.

Having thus described my invention, the following is what I claim as new therein and desire to secure by Letters Patent: 35

1. The design for a cigar-butt cutter shown and described, the same consisting of the U-formed rear journal-bearing, A, knife-holder C c c', and the throat-plate D. 40
2. The knife-holder C, having the claviformed upper extremity, c'. 45
3. The throat-plate D d d' d'' d''' d^{iv}, formed as shown and described.
4. The combination of the claviformed holder C c and the partially-exposed circular disk E.

NAPOLEON DU BRUL.
